[57] **CLAIM**

The ornamental design for a compression sleeves for deep vein thrombosis, as shown and described.

DESCRIPTION

FIG. 1 is a perspective view of the compression sleeve for deep vein thrombosis which illustrates the new design;

FIG. 2 is a top plan view thereof;

FIG. 3 is a front view thereof;

FIG. 4 is a bottom view thereof;

FIG. 5 is a rear view of FIG. 1;

FIG. 6 is a right side view of FIG. 1;

FIG. 7 is a left side view of FIG. 1;

FIG. 8 is a top plan view of a second embodiment of FIG. 1;

FIG. 9 is a front view of FIG. 8;

FIG. 10 is a bottom view of FIG. 8;

FIG. 11 is a rear view of FIG. 8;

FIG. 12 is a right side view of FIG. 8;

FIG. 13 is a left side view of FIG. 8;

FIG. 14 is a top plan view of a third embodiment of FIG. 1;

FIG. 15 is a front view of FIG. 14;

FIG. 16 is a bottom view of FIG. 14;

FIG. 17 is a rear view of FIG. 14;

FIG. 18 is a right side view of FIG. 14;

FIG. 19 is a left side view of FIG. 14;

FIG. 20 is a top plan view of a fourth embodiment of FIG. 1;

FIG. 21 is a front view of FIG. 20;

FIG. 22 is a bottom view of FIG. 20;

FIG. 23 is a rear view of FIG. 20;

FIG. 24 is a right side view of FIG. 20; and,

FIG. 25 is a left side view of FIG. 20.

UNITED STATES PATENT AND TRADEMARK OFFICE
CERTIFICATE OF CORRECTION

PATENT NO. : Des. 376,013
DATED : November 26, 1996
INVENTOR(S) : Sandman, et al.

It is certified that error appears in the above-identified patent and that said Letters Patent is hereby corrected as shown below:

On the cover page, U.S. Patent References, Column 1, line 1, delete "Rubinette" and insert --Robinette-- therefor.

On the cover page, U.S. Patent References, Column 1, line 11, delete "Mumment" and insert --Mummert-- therefor.

On the cover page, Other Publications, lines 1-2, delete "Wrap Around" and insert --Wrap-Around-- therefor

On the cover page, Column 2, in the claim, line 1, delete "sleeves" and insert --sleeve-- therefor.

On the cover page, Column 2, in the Description of the Figures, next to last line, after "and" omit the comma (,).

Signed and Sealed this
Twentieth Day of May, 1997
